UNITED STATES PATENT OFFICE

CARRIE STERNBERG, OF PHILADELPHIA, PENNSYLVANIA

WINDOW CLOTHES RACK

Application filed October 19, 1932. Serial No. 638,479.

My invention relates to new and useful improvements in a window clothes rack and has for one of its objects to generally improve devices of this character whereby a structure of simple formation is provided which will be strong and durable and inexpensive in the cost of manufacture.

Another object of the invention is to provide a frame to be mounted in a window casing for supporting a number of rods slidably assembled in the frame on which clothes or other articles may be hung and which may be used for supporting mattresses, rugs and similar large household things that it is desirable to place in the sunshine or outside air.

A further object of my invention is to construct the frame so that it can be folded, partially folded or "broken" for placement in sash grooves or guideways of the window casing.

A still further object of the invention is to provide the ends of the frame with compressible means to a tight fit for the frame between the sides of the window casing.

Still another object of the invention is the provision of means to support the outer rail of the frame under some conditions.

With these and other ends in view, this invention consists in the details of construction and combination of elements hereinafter set forth and then specifically designated by the claims.

In order that those skilled in the art to which this invention appertains may understand how to make and use the same, I will describe its construction in detail, referring by numerals to the accompanying drawing forming a part of this application, in which:—

Fig. 1 is a perspective of the window clothes rack constructed in accordance with invention, showing it mounted in a window casing.

Fig. 2 is a perspective view of the rack frame per se in a folded position.

Fig. 3 is an end view of one of the rods.

Fig. 4 is a fragmentary side elevation thereof.

In carrying out my invention as herein embodied, 5 represents the frame of my win-

dow clothes rack, and said rack includes two rails 6 and 7, each consisting of two sections 8 and 9 hinged together at their meeting ends by hinges 10. The hinges are opposite each other so that the frame may be folded or broken intermediate its ends.

The rails of the frame are attached to cross bars 11 so as to be held together and maintained in parallelism. In order to strengthen the frame when extended, expanded or in working position, one section, as 8, of each rail is provided at its meeting end with a tenon 12 for registration with a groove or slot 13 in the meeting end of the coacting section 9. The formation of the tenons produces shoulders 14 which engaged the shoulders 15 provided at both sides of the slots.

Through the two rails 6 and 7 are formed a series of aligned holes 16 and two of such holes are formed so that they pass through the rail sections 9 in the region of the slots 13 and through the tenons 12, whereby, a suitable instrument inserted in said holes while the rail sections are in endwise alignment will secure or hold the frame in an open or expanded condition and will prevent accidental folding of the frame.

On the ends of the rail 6 or on the outer ends of the sections 8 and 9 of said rail 6 are mounted compressible members 17, such as rubber headed tacks so that when the frame is placed in a window casing in a folded position and then opened or by the use of sufficient force to straighten out the sections of the rails, said compressible members will be slightly compressed and will snugly fit opposed surfaces of the window casing to hold the frame in place.

Similar compressible members 18 may be placed on the lower surface of the rail 6 near the end or at other suitable locations to engage the window sill to prevent damage thereto which might occur should the hinges engage the window sill.

While the device may be used in any vertical position between the window sill and the upper window sash while the latter is in its elevated position, I prefer that when extra heavy objects are placed on the device

that the said device be in the lowermost position as illustrated in Fig. 1, and when in this position said device may be further supported by brackets 19 projecting downwardly and inwardly in angular positions from the sections of the rail 7, which are of sufficient length to extend below the window sill and engage the outer face of the building below said window sill.

10 After the frame has been properly placed in the window casing, rods 20 of any suitable or desirable length are projected through the series of holes 16 in the two rails and the inner ends of said rods are preferably provided with heads 21 to limit the projection of the rods through the frame rails, but said heads should be small enough to lie between the inner rail 6 of the frame and the lower window sash when the latter is in its lowered position which thus permits the window to be closed while the device is in use and the lower sash prevents the rods from being displaced inwardly. It will be obvious from the above description that one 25 of said rods 20 can be used as the instrumentality for holding the frame in its open position.

A person using this device can project one rod partly through the frame and then hang 30 an article thereon by the use of clothes pins or otherwise and then slide the rod outward another short distance after which another article may be hung thereon, and these operations continued until the rod is filled, 35 after which the same operations may be carried out with as many rods as are necessary to accommodate the articles which are to be hung out. Of course if the device is placed in a window casing so that the rods can be 40 reached from the ground, then all of the rods can be inserted in the frame and positioned outward to their limit and the articles then hung thereon. The device is also useful for airing large objects, such as articles of bed clothing or mattresses in which case all or as many of the rods as are necessary may be placed in their operative positions and the object or objects laid upon the rods.

50 When the device is not in use, it may be readily disassembled and removed from the window casing for storage purposes.

Of course I do not wish to be limited to the exact details of construction herein 55 shown and described as these may be varied within the limits of the appended claims without departing from the spirit of my invention.

Having thus fully described my invention, 60 what I claim as new and useful is:

1. In a window clothes rack, an inner rail consisting of two sections hinged together and adapted to be mounted in a window casing with the ends projecting into opposite 65 sash guideways, said rail having a series of

holes in both of the sections in longitudinally spaced relation, compressible members on the ends of said rail, an outer rail consisting of two sections hinged together and having a series of longitudinally spaced holes 70 throughout both sections of said rail, cross bars on the ends of which are mounted said rails for holding the latter in spaced relation with the holes in both rails in alignment, and rods removably and slidably mounted in the holes in said rails, said rods having heads on their inner ends.

2. In combination, an inner rail consisting of two sections, the meeting end of one section having a slot formed therein, a tenon formed with the meeting end of the other section for entrance into the groove of the first mentioned section when the two sections are in endwise alignment, a hinge connecting said sections, compressible members on the outer ends of said inner rail, other compressible members on the lower edge of said inner rail, an outer rail consisting of two sections, one of said sections having a groove formed in its meeting end, a tenon forming with the meeting end of the other section for projection into the groove with the two sections are in endwise alignment, a hinge connecting the two sections of said outer rail, cross bars connected to said outer rail, cross bars connected to said rails to hold the latter in parallel spaced relation, angular brackets depending from the outer rail and projecting inwardly, both of said rails having a series of holes therethrough, the ones in the outer rail being in alignment with the ones in the inner rail and one of the holes through each rail passing through a tenon and the material on both sides of a groove, rods slidably and removably mounted in said holes and when in place projecting through the holes of both rails and that rod which passes through the holes in the region of the tenons temporarily holding the rail in open positions but upon removal thereof permitting the rails to be folded for mounting in a window casing or removal therefrom, and heads on the inner ends of said rods to prevent accidental outward displacement of said rods.

In testimony whereof, I have hereunto affixed my signature.

CARRIE STERNBERG.
